UNITED STATES PATENT OFFICE.

CHARLES MESSICK, JR., OF HACKENSACK, NEW JERSEY.

CABLE-TRAMWAY SUPPORT AND SHIELD FOR AERIAL RAILWAYS.

SPECIFICATION forming part of Letters Patent No. 780,434, dated January 17, 1905.

Application filed April 21, 1904. Serial No. 204,192.

To all whom it may concern:

Be it known that I, CHARLES MESSICK, Jr., a citizen of the United States, and a resident of Hackensack, in the county of Bergen and State of New Jersey, have invented a new and useful Improvement in Cable-Tramway Supports and Shields for Aerial Railways, of which the following is a full, clear, and exact description.

10 The purpose of the invention is to provide a new cable-tramway shield especially adapted for aerial railways, which is a removable approach-plane, independent of the cable yet resting upon it, and to provide a shield of the above character which is practicable for long spans and which will be economic both with respect to the construction and erection and which will not tend to lacerate the cable. The detail construction lies in the shield made of

15 two independent parts, one for each direction of the travel of the car; but in the event a track is to be traveled in one direction only the shield is constructed, preferably, in but one part—that is, the part extending toward the approaching car.

Another purpose of the invention is to so construct the improved shield or shields as to obtain a plane which will automatically accommodate itself to the ascension of the car to the point of support without retarding the progress of the car and so that after the car has risen to such height it will pass onto the cable without causing an impact or vibration.

An additional feature of my invention is that the improved shield can be made stronger and at much less expense than any of which I have knowledge, the only strain which it is called upon to withstand being the weight of the car at its center. The shield is supported at one end by a cable and at the other end by a bracket-hanger or like device.

Another feature of the invention is to so construct the shield that it rests upon the cable by its own weight and requires no internal member to hold it from lifting up from the cable, and, further, as the cross-bolts employed are only used to increase the rigidity of the shield the shield may be removed and renewed or replaced without disturbing the cable on the support.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a perspective view of the improved shield of the double type and a section of cable in connection with which it is used. Fig. 2 is a side elevation of the shield shown in Fig. 1, a car having just passed over the shield, a section of cable and a portion of the car being also illustrated. Fig. 3 is a sectional plan view of the central portion of the shield illustrated in Figs. 1 and 2. Fig. 4 is a transverse section taken practically on the line 4-4 of Fig. 1. Fig. 5 is a side elevation of a section of cable and a slightly-modified form of shield. Figs. 6, 7, and 8 show side elevations of the said shield wherein the cable is within the shield. Fig. 9 is a sectional plan view of the form of shield shown in Figs. 6, 7, and 8. Fig. 10 is a side elevation of what may be termed a "single" shield. Fig. 11 is a side elevation of a section of cable and its supports and two of the shields used in connection with the cable, one at each support; and Fig. 12 is an enlarged side elevation of one of the supports and an end of the car and likewise an end of the shield, the cable being in section. Fig. 13 is a vertical section through a terminal loop or hood for the shield, illustrating a construction whereby the loop is prevented from chafing the cable under the weight of the car. Fig. 14 is a view similar to that shown in Fig. 13, but illustrating a slightly-different construction of loop; and Fig. 15 is a partial side elevation of the shield and a sectional side elevation of the loop or hood pivotally connected with the shield.

In Figs. 1, 2, 3, and 4, A represents the cable, and B the improved shield therefor, and this shield is constructed in two pivotally-connected sections b and b'. The sections are of like construction and are made from T-iron, embracing a web 10 and a horizontal flanged head 11, on which the cable rests, and the said cable passes beneath loops or hoods 12, 100

secured at the outer ends of the sections of the said shield, the heads 11 of the sections being cut away at that point, and spacing-blocks 13 are secured to opposite sides of the webs of the sections of the shield. These spacing-blocks and the loops are held together by means of suitable bolts 13^a, as is best shown in Fig. 4. The sections of the shield are pivoted between upwardly-extending and connected lugs 14, secured upon bracket-arms 15, extending outward from the supporting-posts 16 for the cable, as is illustrated in Figs. 11 and 12. The pivotal connection between the sections of the shield is effected by attaching plates or straps 17 and 18 in any suitable or approved manner to the web members of the sections *b* and *b'* of the shield at their inner ends, and these plates or straps 17 and 18 extend beyond the inner ends of the sections of the shield, as is shown in Figs. 1 and 3, and are outwardly bowed. Corresponding outwardly-bowed members are made to overlap each other between the lugs 14, a pivot-pin 19 being passed through the said lugs and the overlapping inner ends of the said straps 17 and 18, as is also best shown in Figs. 1 and 3. In the space between the bowed portions of the straps 17 and 18 a guide-pulley 20 is pivoted on the pin 19, and the said cable A passes over this guide-pulley 20 and through the loops 12 between the upper portions of the loops and the flanged or upper edge portions of the sections of the shield. It will be observed that each section 35 acts independently of the other and that when a car H approaches any of the sections its wheels will pass readily over the upper edges of the loops 12, which are rounded, and the cable is effectually prevented from buckling 40 while the car is moving over the section which it had approached. In this manner it will be obvious that the speed of the car will not be retarded by any buckling or loops which ordinarily form in a cable when a car approaches 45 a support for the cable.

In Fig. 5 I have shown a slight modification of the structure shown in Figs. 1 and 2, in which the cable is designated as A' and the shield as C, being constructed in two sections 50 *c* and *c'*, likewise made of T-iron. These sections *c* and *c'* are provided at their outer ends with loops 12^a, corresponding to the loops 12 in the form shown in Fig. 1, and near the inner end of each section *c* and *c'* of the shield 55 C loops 12^b are formed, and the cable passes beneath four loops instead of but two. The pulley 20 is therefore omitted. Furthermore, under this form of shield the two inner ends are not brought together, but are independently pivoted in lugs 14, carried by bracket-arms 15, the lugs and the bracket-arms being the same as heretofore described.

In Fig. 6 the shield is designated as D, and as in the other views it is divided into two independently-pivoted sections, (designated as

d and *d'*.) This form of shield D differs from the other forms of shield described, inasmuch as the sections are in the form of an inverted U in cross-section, and the cable A² extends within the sections of the shield below the upper surface of the same. The sections *d* and *d'* of the shield meet at their inner ends on a diagonal line 22, (shown in Fig. 9,) and the two sections are pivotally connected to the lugs 14 and bracket-arm 15, heretofore alluded to, by means of a single pivot-bolt 23, as is also shown in Fig. 9. Bolts or rivets 24 are passed through the lower portions of the sections *d* and *d'* of the shield for the purpose of strengthening the same, and sundry of these rivets or bolts are utilized as lower supports for the cable A². Furthermore, in the construction of this form of the shield friction or guide rollers 25 are located in each section near the meeting ends of the sections, and these rollers 25 are below the cable A², serving as roller-supports therefor. It will be observed that under this construction the action of the sections of the shield will be identical with that of the constructions herefore described.

In Fig. 7 I have illustrated another departure, in which E represents the shield, and this shield, as in the former constructions, is in two parts *e* and *e'* and is U-shaped in cross-section, as has been described relative to the construction shown in Fig. 6; but preferably the lower edges of the sections of the shield at their outer ends are upwardly inclined, as shown at 27, and the cable A³ passes through the sections of the said shield beneath their upper portions, as in Fig. 6. Bolts or rivets 26 are employed to strengthen this construction of the shield, and sundry of them are utilized to support the lower portion of the cable A³, more of such rivets being used for that purpose than in the construction shown in Fig. 6. The sections *e* and *e'* at their inner abutting ends are connected with what may be termed a "rule-joint" 28, a pivot-pin 29 passing through the knuckles and likewise through lugs 14, carried by a bracket-arm 15, as in the other constructions named. The cable A³ under this construction is supported at its center by a grooved pulley 30, corresponding to the pulleys 25 and the pulley 20, and this guide-pulley 30 is located below the cable, yet in engagement therewith, and is pivoted on the pivot-pin 29 between the members of the sections of the shield where the said members connect. The upper connection between the two sections *e* and *e'* is preferably a straight one, although the diagonal contact shown in Fig. 9 may be employed, if so desired.

In the construction shown in Fig. 8 the shield F therein illustrated is divided, as are the other shields, into two sections *f* and *f'*. These sections are also inverted-U shape in cross-section and are so connected as to have

the inclined abutting edges shown in Fig. 9. The section f , however, extends beyond the lugs 14, utilized as pivots and carried by the above-mentioned bracket-arm 15. The pivot-pin 30° is passed through the section f near its inner end and through the aforesaid lugs 14. The section f' of this shield F is pivoted to the section f at one side of the sustaining-lugs 14 by means of a suitable pin 31, and on this pin a friction-roller 32 is mounted to turn, adapted for sustaining a guiding connection with the bottom portion of the cable passing through the said shield and designated as A⁴. This cable is also supported by one or 15 more brace pivots or bolts 34 and by means of rollers 33, located at the outer end of one or both of the sections f and f' . It will be observed that the operation in this form of the device is the same as that described in 20 connection with the forms heretofore mentioned.

In Fig. 10 I have illustrated what is a single form of the shield, in which but one member G is employed, and this member is inverted-U shape in cross-section and is pivotally attached to a horizontal arm G'. The said arm is sustained in any suitable manner by the bracket-arm 15 referred to and is provided with top and bottom flanges 35, the upper flange or head constituting a guide or bearing for the wheels of the carriage H, and normally the upper or tread surface of the upper head or flange 35 is in horizontal alinement, or practically so, with the outer upper 30 surface of the arm. The arm G is likewise provided with connecting or strengthening bolts or rivets 38, and some of these are employed as guides for the lower portion of the cable A⁶, which passes through the said arm 40 G, and the said cable likewise passes beneath the upper flange 35 of the bar G'. It may be here stated that preferably this bar is in the shape of a channel-iron, and a suitable spacing-block 36 is employed in the channel 45 of the channel-iron where the arm G is pivoted thereto by means of a suitable pivot-pin 37. The abutting connection between the channel bar or iron G' and the arm G may be either straight or diagonal, as occasion may 50 require or as may be found most desirable to permit free lineal movement of the cable. In fact, the office and object of each and every form of the device above described is to provide tracks for cables of tramways to hold 55 the cables in place on brackets and yet permit the passage of the car over the brackets with a minimum of jar and pounding, for which device the essential parts are a rest for the cable of such shape that the cable will not 60 cut or chafe by resting on it, this rest to be located close to the center of the bracket, and the cable is directed in any of the ways illustrated and described either over or beneath the sustaining and guiding shields.

65 In Fig. 13 I have illustrated the outer ter-

70 minal portion of a loop 12 for a shield as provided with an upward curve 40 at the inner face of its upper portion, or such portion of the loop may be said to be more or less convex. The idea of giving this formation to the loop 12 is to prevent the loop from chafing or cutting the cable as the weighted car passes over it.

In Fig. 14 I have illustrated a slight modification in the formation of the loop 12, wherein at the upper portion of the outer end of the loop the entire loop is slightly upwardly bent, so as to present an inner convexed surface 41 and a more or less outer concaved surface 41^a, whereas under the construction 80 shown in Fig. 1 the outer surface of the loop 12 above the curved portion 40 is practically straight.

Under the construction shown in Fig. 15 the loop 12 is shown as pivoted by a single 85 bolt 42 to the outer end of a member B of the shield, and the inner face of the said loop at its upper portion is concaved or curved upwardly and outwardly at each end, as is shown at 42°. Under this latter construction the 90 loop 12 will always preserve a vertical position and will be in the same vertical plane with a line drawn vertically through the pivot portion of the shield, and the loop being curved at each end where it engages with the 95 cable will absolutely prevent the said loop from having detrimental wear on the cable and will assist the loop in preserving its vertical position.

Having thus described my invention, I claim 100 as new and desire to secure by Letters Patent—

1. In a supporting and guide shield for cables of cable-tramways, a support, an arm pivoted at or near one end on the support and extending toward the approaching car, and 105 means for maintaining the cable in place with reference to an arm, as described.

2. In a supporting and guide shield for the cables of cable-tramways, a support, shields having pivotal relation to each other and to 110 the support, the said shield having guides for the cable, as described.

3. In a supporting and guide shield for the cables of cable-tramways, a support, a shield consisting of two independent sections having 115 pivotal relation to each other and pivotal relation to the support, and loop-guides for the cable, as and for the purpose set forth.

4. In a supporting and guide shield for the cables of cable-tramways, a support, a shield consisting of two independent sections having 120 pivotal relation to each other, and pivotal relation to the support, loop-guides for the cable, and roller-guides for the cable independent of the loop guides, as described.

5. A support for cables, and shields for the cables having guides therefor and constructed in sections having pivotal relation to the support, the sections having opposed independent action relative to each other, as described. 125 130

6. In a supporting and guide shield for the cables of cable-tramways, a support, a shield for the cable, inverted-U shape in cross-section, receiving the cable between its members, the said shield being in two longitudinal sections, roller-supports for the bottom portion of the cables, and a pivotal connection between the sections of the shield and the said support, the sections of the shield being provided with diagonal striking-surfaces at their inner abutting ends, as and for the purpose described.
7. In a guide-shield for the cables of cable-tramways, a shield, and a guide-loop for the cable carried by the shield and provided with an upwardly-curved inner surface at its upper portion, as described.
8. In a support and guide shield for cables of cable-tramways, a shield, a support to which the shield is pivoted, and a guide-loop pivoted at the outer end of the shield, the said guide-loop having the under faces of its terminal portions at its ends curved in an upward direction, as set forth.
9. In a supporting-guide for cables, a sup-

port, a truss comprising a rigid member located principally beneath the cable and hinged near the support, hung near its free end from the cable and adapted to prevent the cable bending between the free end and the support. 30

10. In a supporting-guide for cables of a cable-tramway, a support, and arms each pivoted at one end to the support and resting on the cable, the arms extending toward the approaching car, for the purpose set forth. 35

11. In a supporting-guide for cables, a support, two arms extending from the support, pivoted near the support and having their free ends resting on the cable, the arms having sufficient depth beneath the cable to act as a truss and prevent the bending of the cable between the support and the free ends of the guides. 40

In testimony whereof I have signed my name to this specification in the presence of two subscribing witnesses.
